UNITED STATES PATENT OFFICE.

JULIUS C. SULLIVAN, OF WARREN, PENNSYLVANIA.

PINCH BAR OR CAR MOVER.

Application filed January 29, 1924. Serial No. 689,357.

To all whom it may concern:

Be it known that I, JULIUS C. SULLIVAN, a citizen of the United States, residing at Warren, in the county of Warren and State 5 of Pennsylvania, have invented new and useful Improvements in Pinch Bars or Car Movers, of which the following is a specification.

This invention relates to improvements in 10 pinch bars or car movers for moving railway cars when it is desired to shift them from one location to another, as for example, upon switches and side tracks at railway stations, industrial plants and other places.

15 The primary object of the invention is to generally simplify and strengthen and render more durable a pinch bar or car mover and adapt the same for application with equal facility and effectiveness to rails 20 of different dimensions and cause a tighter grip of the rail engaged as the force applied to the pinch bar for moving the car increases. A further object of the invention is to form the forward or toe portion of the 25 body of the pinch bar and the shoe movably carried by the operating lever for engagement with a wheel rim of precisely the same concave curvature and cause a more effective operation of the said parts relatively 30 to the wheel, and to so mount the shoe that it will be disposed in its applied position at an angle of about 45° relatively to the axis of the wheel engaged. A further object of the invention is to assemble the wheel rim 35 engaging shoe and the operating lever in such manner that the mounting of the shoe will be materially strengthened and wear on the fulcrum means or pivot device therefor reduced to a minimum. A still further object 40 of the invention is to eliminate from the general construction of the improved pinch bar or car mover all small parts and springs or other devices that are liable to become disordered or broken.

45 With these and other objects and advantages in view, the invention consists in the construction and arrangement of the several parts which will be more fully hereinafter described and claimed.

50 In the drawing:

Fig. 1 is a side elevation of a portion of a car wheel and rail, showing the improved pinch bar or car mover in operative position with relation thereto, a portion only of the 55 operating lever being shown;

Fig. 2 is a top plan view of the improved

pinch bar or car mover with the operating lever broken away;

Fig. 3 is a rear end elevation of the improved pinch bar or car mover shown applied to a rail in dotted lines, the operating lever being broken away;

Fig. 4 is a detail perspective view of the shoe; and

Fig. 5 is a detail perspective view of the 65 forward end of the operating lever to which the shoe is attached.

The numeral 5 generally designates the clamping or body member, which is of suitable dimensions but preferably of cross sectional extent less than the width of the top surface of the head or ball of a railroad rail and also of a length sufficient to render the complete device practicable in performing the function for which it has been devised. 70 It is proposed to construct the clamping or body member 5 of suitable metal and to render the same strong and durable but at the same time light, or minimize as much as possible the amount of metal in the formation 80 thereof without detracting in the least from the strength and durability of said member. The clamping or body member 5 has its forward extremity reduced and tapered, to provide an extension or nose 6 having a lower 85 straight edge 7 and an upper concave face 8. About midway of the said extension or nose 6 depending arms 9 are located, to facilitate placement of the forward portion of the member 5 on the rail, said arms 9 extending 90 downwardly far enough to obstruct lateral disengagement of the extension or nose 6 from the rail, and thereby facilitate disposition of the extension or nose 6 with relation to the rim and flange of a car wheel. 95 The depending arms 9 are separated by a space of such transverse length as to adapt the extension or nose 6 to be applied over rail heads varying in width without engagement of the said arms with the opposite side 100 portions of the rail heads. The entire lower edge of the clamping or body member 5 is straight, and in the rear extremity of the member a rail head clamping die 10 is removably mounted and comprises an upwardly projecting flat shank 11 fitting in a transverse slot 12 and having opposite openings 13 therethrough, to register with similar openings 14 in the rear extremity of the member, to receive removable fastening devices or cotter pins 15. The rear extremity 105 of the member 5 is in the form of a T-head

110

16, as clearly shown by Figs. 2 and 3, so as to give ample width for mounting the die 10 and provide for practical transverse spanning of a rail head by the said die. As shown by Fig. 3, the die is formed with a central recess 17 having divergent straight side walls 18, which are shown as formed with biting edges by the dotted lines 19, so as to cause the said die to firmly bite the side portions of a rail head in the manner shown by Fig. 3. The recess 17 has a maximum width greater than the widest rail head known in the art of rail construction, and such recess is also of a depth sufficient to permit the die to fit rail heads and serve as a reliable and positively acting rear or heel stop means with relation to rail heads of different widths; and whereby the clamping or body member 5 may be maintained in its applied position relatively to a car wheel rim and flange without liability of backward slipping movement when the power for moving the car wheel is applied in a manner which will be presently explained. The die 10 is rendered removable from the head 16 to permit sharpening of the biting edges 19, or when the die becomes worn to such an extent as to interfere with its efficiency, permit replacement of said die by another similar device. The upper part of the clamping or body member 5 at a point slightly in advance of the rear die holding head 16 is formed with opposite fulcrum ears 20, which stand above the remaining portion of the said member, and in advance of these fulcrum ears the member is also formed with an approximately semi-circular recess 21. The clamping or body member 5 is of hollow construction and the recess 21 is formed in the two side units 22 immediately in advance of the fulcrum ears or projections 20. The clamping or body member 5 in advance of the substantially semi-circular recess 21 also projects upwardly as at 23, and provides the advance termination for the said recess, this advanced elevated portion of the member 5 constituting the rear part of the extension or toe 6 having the upper bearing or engaging side, which is given the concave curvature 8 as hereinbefore described. This upper side 24 is formed with openings 25, to lighten the same and permit any matter that would attend to accumulate on the said side to fall through the openings 25 and maintain this upper side portion of the toe or extension always in proper condition for engagement with the rim of a car wheel. This open construction may be varied and the formation of the same does not in the least detract from the strength and durability of this part of the member 5 nor from the efficiency in surface engagement relatively to the rim of a car wheel.

An operating lever 26 is mounted in the clamping or body member 5, and essentially

comprises a socket 27 for the reception of the lower end of a hand or lever bar 28, and from the lower end of the socket 27 a shank 29 extends and is slightly enlarged, as at 30, for interposition between the fulcrum ears or projections 20, and therethrough and through the said ears or projections a pivot pin or bolt 31 is removably inserted. The shank 29 continues beyond the fulcrum ears or projections 20 and terminates in a central hinge flange or coupling member 32 having a central opening 33. To strengthen the shank 29 the latter has upper and lower laterally projecting ribs or flanges 34, which terminate at the rear portion of the coupling member 32 and the laterally projecting thrust-takeup flanges 35 provide as a whole a very efficient means for the assemblage and movable mounting of a pressure shoe 36 having lower fulcrum ears or disk members 37, which are separated by a slot 38, the said ears or disk members 37 each having a central opening 39 therethrough, and these two openings are in transverse alinement and are adapted to aline with the opening 33 through the coupling member 32. The shoe 36 is gradually enlarged or flared outwardly from the coupling disks 37, to form a pressure head 40 having an outer concave bearing face or side 41, which is in the same arc of curvature as the concave bearing face 8 of the extension or nose 6, so as to insure a snug fitting of the extension or nose and the shoe relatively to the car wheel rim engaged thereby. The coupling disks 37 are applied over opposite sides of the coupling member 32 with the latter loosely projecting upwardly into the slot 38, and the pivotal connection is completed by inserting a pin 42 through the coupling disks 37 and coupling member 32. The coupling disks 37 rest within the thrust-takeup flanges 35 and the latter flanges relieve the coupling pin 42 of thrust or thrust wear to a very material extent, and moreover, the said flanges 35 assist in producing a forceful engagement of the concave bearing face or side 41 of the head 40 of the shoe 36 with the car wheel rim. The recess 21 gives a clearance at opposite sides of the intermediate portion of the clamping or body member 5 for manipulation of the shoe when found necessary, and the rear upper portion of the extension or toe 6 is longitudinally slotted as at 43, to give freedom of action to the shoe, and at a suitable distance below the upper projection 23 of the rear portion of the extension or toe 6 a stop pin 44 is mounted and extends transversely across the slot 43, to prevent the shoe 36 from falling below a certain level and to insure a self positioning or automatic op-

eration of the shoe to bring the concave face 41 thereof in contact with the wheel rim.

It will be seen from the foregoing that the number of loose parts of the improved pinch 5 bar or car mover are reduced to a minimum, and that all springs and other frail structural devices usually found embodied in pinch bars or car movers are entirely eliminated. Moreover, all of the parts of the 10 present improved pinch bar or car mover are adapted to be readily associated and dissociated and capable of replacement without dispensing with the remaining parts of the pinch bar or car mover that might be still 15 practicable serviceable.

In the operation of the improved pinch bar or car mover, it is positioned under the rim of a car wheel, which may be one of the rear wheels of a group 1, 2, 3 or more cars, 20 with the concave engaging face 8 of the extension or nose 6 close under the car wheel rim, and when the body member 5 is thus positioned, the depending arms 9 will stand on opposite sides of the rail head as shown 25 by Fig. 3 and the die 10 will be in gripping relation to the rail head as also shown by the latter figure. The operator then presses downwardly on the hand or lever bar 28 and forces the shoe 36 upwardly, to effect an 30 engagement of the concave surface or side 41 with the car wheel rim as shown by Fig. 1, and by the application of a comparatively small amount of power on the operating lever as a whole, the lever will be moved 35 and, as found necessary, the entire device may be shifted longitudinally over the rail head until the movement of the car wheels is sufficient to start self-movement of the car or cars. As the engaged car wheel rotates 40 it will be obvious that the shoe 36 will move upwardly and at certain intervals the shoe will be reset or caused to engage the car wheel as shown by Fig. 1 and thereby effectively set up a rotation of the car wheel 45 and propulsion of the car as desired.

The die 10 does not have to be adjusted to fit and positively engage rail heads of different width, the reliable biting action of this die or heel stop being automatic in view of 50 the shape of the recess 17, and the biting edges 19 of the die are located near the rear side thereof, so as to permit the clamping or body member 5 together with the parts attached thereto to be more readily moved forward over the rail during the operation of 55 the improved pinch bar or car mover. The forward extremity of the shank 29 is freely movable downwardly into the opening between the side units 22 to a certain extent 60 during placement of the shoe 36 in contact with the wheel rim, and the recess renders the pivotal connection for the shoe relatively to the forward end of the shank 29 of the operating lever readily accessible for applying and disconnecting the shoe. The

pivot pin 31 engaging the ears or projections 20 and the shank 29 is rendered easily removable by engagement with opposite ends thereof of fastening devices of well known types as clearly shown by Fig. 1, and consisting of cotter pins 45. The provision of the T-head 16 at the rear extremity of the clamping or body member 5 and the projection of the opposite extremities of the said head beyond the side portions of the member permits the fastening devices or cotter pins 15 to be readily inserted or withdrawn as may be necessary in the removal and replacement of the die or heel stop 10.

The improved pinch bar or car mover as hereinbefore described is capable of use in applying ample power to the car wheel to move a car without unnecessary resistance, and after the clamping or body member 5 has been placed in proper position, it will be 80 prevented from slipping rearwardly by the die or heel stop 10 and always insure engagement of the concave face 41 of the shoe 36 with the portion of the car wheel rim desired to obtain the best results. The biting edges 90 17 of the die 10 are especially effective when engaging rail heads having grease or ice thereon, and by the positive placement and prevention of movement due to engagement 95 of the die 10 with the rail head, the operator is at all times shielded against accident. Moreover, the location of the die or heel stop in rear of the fulcrum point of the operating lever 26 will cause the shoe 36 100 to engage the rim of the car wheel at a proper point, or mainly at an angle of 45°, to give the most advantageous leverage and which is further insured by the similarity of curvature of the upper face 8 of the extension of toe 6 and the shoe 36.

In addition to the functions of the improved pinch bar or car mover as hereinbefore explained, it may also be practically employed at times for holding or chocking wheels, either on a grade or on a level, whereby accidental movement of a car from a desired position is prevented, and in this particular use it is obvious that the rear, transversely extending rail head-engaging means or die will effectively operate to fix the improved pinch bar or car mover in its applied position.

What is claimed as new is:

1. In a car moving device of the class specified, the combination of a body member having a lower straight edge and a forward reduced extension with an upper concave face to engage the rim of a car wheel, the body member having a longitudinal opening extending through the top portion thereof, an operating lever pivotally connected to the upper portion of the body member near the rear extremity of the latter, the lever having a front extremity projecting beyond its fulcrum point and movable in 130

the said longitudinal opening; a pressure shoe pivoted to the forward end of the reduced extension of the lever; the attaching means for the shoe relatively to the lever having a minimized lateral extent to permit the shoe to depress in and move upwardly through the said longitudinal opening, the shoe having a concave face to engage the rim of a wheel, and track-engaging means depending from the rear portion of the body member and disposing the bottom of said member normally at an angle relatively to the track rail to which it is applied to give the reduced forward extension a more effective wedging action with relation to the rim of the car wheel.

2. In a car moving device of the class specified, the combination of a gripping body member having a lower straight edge and a forwardly extending reduced nose with an upper concave wheel-rim-engaging face, the body member having a central longitudinal opening continuing through the top thereof, a lever pivotally connected to the upper portion of the body member and having an extremity projecting beyond its pivotal point which is movable into the said opening, a shoe pivotally connected to the forward end of the lever and having a concave face to engage the rim of a car wheel, and means for holding the body member in engagement with a track rail and for disposing the latter at an angle of inclination relatively to a track rail to obtain a more effective wedging action of the reduced extension and shoe relatively to the rim of a car wheel.

3. In a car moving device of the class specified, a gripping body member formed with a forward reduced extension to fit over the rim of a car wheel and having a lower straight edge, a rail-engaging die secured in the rear extremity of the body member and depending to such an extent as to effect an inclined position of the said member when the device is applied; an operating lever fulcrumed in the upper portion of the body member in advance of the rear end of the latter, and a pressure shoe pivotally connected to the front end of a part of said lever and having an upper concave wheel-rim-engaging face of the same arc of curvature as the upper face of the reduced extension of the lever, the attaching means for the shoe relatively to the lever having a minimized lateral extent to permit the shoe to depress in and move upwardly through the said longitudinal opening, the shoe having a concave face to engage the rim of a wheel, and track-engaging means depending from the rear portion of the body member and disposing the bottom of said member normally at an angle relatively to the track rail to which it is applied to give the reduced forward extension a more effective wedging action with relation to the rim of the car wheel.

4. In a car moving device of the class specified, a rail-engaging gripping body member; an operating lever fulcrumed on the upper portion of said member near the rear end of the latter and having a forwardly projecting extremity in advance of the fulcrum point thereof, the gripping member having a longitudinal opening extending through the top portion thereof into which the forwardly projecting extremity of the lever is freely movable, a pressure shoe fulcrumed to the forwardly projecting extremity of the lever, the shoe and the lever having interacting thrust means to relieve the fulcrum device for the shoe of strain; a transversely-extending stop device mounted in the upper portion of the body member across the longitudinal opening of the latter to limit the downward movement of the shoe, and means connected to the rear end of the body member for engagement with a rail for normally tilting the said body member at a forward and downward angle to dispose the forward extremity of the body member and the shoe opening, a shoe pivotally connected to the operating lever for engagement with a portion of a wheel rim, the rear part of the body member being laterally extended in the form of a T-head to give the same a greater bearing extent, and a transversely extending die member in said T-head having a shank removably secured in the rear extremity of the body member and provided with a central upwardly converging recess opening through the lower edge thereof to transversely span and engage rail heads varying in extent and whereby the die member automatically adapts itself for engagement with rail heads of different dimensions.

5. In a car moving device of the class specified, the combination of a gripping body member having an operating lever movably connected thereto, a pressure shoe pivotally attached to the forward end of the operating lever for engagement with a portion of a wheel rim, the rear part of the body member being laterally extended in the form of a T-head to give the same a greater bearing extent, and a transversely extending die member in said T-head having a shank removably secured in the rear extremity of the body member and provided with a central upwardly converging recess opening through the lower edge thereof to transversely span and engage rail heads varying in extent and whereby the die member automatically adapts itself for engagement with rail heads of different dimensions.

In testimony whereof I have hereunto set my hand:
JULIUS C. SULLIVAN.
